FELTING NEEDLE

Edson P. Foster, Manitowoc, Wis.

Application October 12, 1942, Serial No. 461,704

18 Claims. (Cl. 28—4)

The present invention relates to an improvement in felting needles and further has to do with a method and apparatus for providing barbs or spurs in felting needle stock.

Felting machines are well known and are employed for matting and compacting loose fibrous materials, such as wool, hair and fur or a combination of these or other analogous materials. It is the general practice in the art to deliver the fibrous material to be compacted upon a slowly moving endless belt conveyor above which a two-part needle plate, having a large number of felting needles secured therein, is disposed. This plate is mounted for rapid vertical reciprocatory movement, above the conveyor belt. The felting needles referred to have barbs on the body portion thereof, which upon downward movement of the plate with respect to the conveyor, engage the fibers of the material and function to interlace the fibers together. These barbs are so formed as to free themselves of the material upon upward movement of the plate. Upon continued repetition of the upward and downward movement of the plate the fibrous material is compacted and interlaced to form a mat. Machines of the type referred to may be suitably designed so that any desired degree of compacting and matting of such fibrous material, within limits, may be attained.

Generally, the needle plates for supporting the felting needles comprise a base member and a superimposed clamping member. The base member is provided with a suitable number of apertures through which the needles are inserted. The needles are provided with securing elements which are adapted to seat upon the top surface of the base member. The clamping member and base member are then bolted or otherwise secured together rigidly clamping between them the securing elements at the upper ends of the needle shanks.

It is old in the art to provide the body portion of a felting needle with barbs by striking the edges of the body portion with a barbing die at spaced intervals therealong to form barbs which protrude outward therebeyond. In mounting felting needles of this form the apertures in the base member of the needle plate must be of sufficient diameter to permit passage therethrough of the protruding barbs and since it is desirable to have the shank of the needle fit tightly in the base member, the needle must be made from a blank of round stock the body portion of which is swaged to provide the edges in which the barbs are formed and leaving the

shank of the needle cylindrical so that it may be snugly received in the aperture of the base plate. This form of needle is objectionable since the swaging operation of the prior art weakened the needle and also adds materially to the cost of production which is an important consideration in this art. Also, the barbs protrude beyond the edge of the needle and are rapidly worn away in use requiring their frequent replacement.

10 It has been proposed in order to overcome the aforesaid objections to this form of felting needles to cut slots in the body portion of the needle to provide downwardly directed barbing spurs which lie within the body portion of the needle.

15 These slots have been of two forms, the first of which and the earliest in the art was of V-shape, and the second and later form being defined by a slot having upper and lower substantially parallel walls which are connected by an end wall substantially perpendicular to the upper wall. However, both of these needles are objectionable in that by slotting the body to form the spurs the needle is considerably weakened since a portion of the metal is removed in the cutting operation

20 substantially reducing the cross-sectional area through the slots. Furthermore, by forming the spur in either manner the working surface is of triangular configuration one corner of which forms the point of the spur with the working surface extending inwardly and upwardly into the body of the needle. With this form of spur the fibers have a tendency to creep to the point of the spur and slip off so that they will not be interlaced.

It is an object of my present invention to provide a felting needle in which the spurs do not extend beyond the periphery of the body of the needle and which is formed by displacing material in the body of the needle to provide for increased mechanical strength.

It is a further object to provide a felting needle having a spur formed by downwardly and angularly inclined surfaces which intersect to form a working edge extending inwardly of the needle above a recess providing access for the material to the spur. Preferably, the spur and recess are formed by displacing material which is disposed adjacent the recess so that the cross-sectional area through the recess is substantially equal to the cross-sectional area of the stock. Still more specifically, if desired, material above the spur may be displaced so that a portion of the working edge will be of arcuate configuration with the outermost end thereof directed downwardly and inwardly of the body of the needle.

My present invention also contemplates the provision of a novel method and apparatus for forming a felting needle with spurs of the character above referred to.

A further preferred specific feature of my invention resides in the provision of a cylindrical sleeve member which is adapted to be carried by the base of the needle plate to receive a felting needle of uniform polygonal cross-section throughout its length, the sleeve being provided to engage the edges of the shank portion of the needle to prevent lateral displacement thereof and greatly reducing breakage in operation.

Other objects and advantages of my invention will appear from the detail description.

Now, in order to acquaint those skilled in the art with the manner of utilizing my invention I shall describe in conjunction with the accompanying drawings certain preferred embodiments of the invention.

In the drawings:

Figure 1 is a diagrammatic side view of a known form of felting machine, illustrative of the use of the needle of my invention;

Figure 2 is an elevational view of a needle of my invention mounted in a sleeve secured in the needle plate of a felting machine, the sleeve being shown in section, and the needle plate being shown fragmentarily and in section;

Figure 3 is a sectional view taken substantially on line 3—3 of Figure 2 and looking in the direction of the arrows, on an enlarged scale;

Figure 4 is a greatly enlarged partial elevational view of the body portion of one form of my improved needle;

Figure 5 is a greatly enlarged partial elevational view of the body portion of another form of my improved needle;

Figure 6 is a diagrammatic side view of an apparatus for making the needles of my invention; and

Figure 7 is a detail sectional view on a reduced scale taken on line 7—7 of Figure 4; and

Figure 8 is a detail sectional view on a reduced scale taken on line 8—8 of Figure 4.

Referring now to the drawings, I have illustrated diagrammatically in Figure 1 a known form of felting machine 1, in which the needle of my invention may be used. Loose fibrous material such as wool, fur, hair or the like is indicated at 2 and is fed by means of a suitable chute 3 onto an endless belt conveyor 4, which is trained over a pair of wheels 5 mounted for rotation on shafts 6, one of which may be driven in any suitable manner.

A two-part needle plate 7 reciprocated in any suitable known manner, is disposed above the conveyor belt 4. Felting needles 8 are suitably fixed in the needle plate and serve to compact and interlace the fibrous material 2 upon the upper run of belt 4, in the reciprocation of the needle plate, as previously stated. A second conveyor 9, which may be similar to the conveyor 4, receives the matted material and conveys it away from the conveyor 4.

In Figure 2 I have shown a felting needle 10 embodying my invention mounted in the needle plate 7 of a felting machine. This plate comprises a base member 11 and a clamping member 12. The base apertured to receive a cylindrical sleeve 13, one for each felting needle, which sleeve is provided with a flanged end which rests upon the upper surface of the base member 11. It will be understood that if desired the base member 11 may be countersunk to receive

the flange of sleeve 13. The needle of my invention preferably is formed of a piece of stock of substantially uniform square cross-section. It will be understood, however, that stock of other cross sectional configuration is contemplated within the broader aspects of my invention. Needle 10 comprises a body portion 14 and a shank portion 15. The lower end of body 14 is pointed at 16 to facilitate penetration of the fibrous material. The upper portion of shank 15 may be bent at substantially right angles providing a securing element 17 adapted to be clamped between clamping member 12 and base member 11 of the needle plate and in engagement with the flange of the cylindrical sleeve 13. The inner diameter of the cylindrical sleeve 13 is such that the needles 10 fit tightly therein with the corner edges thereof in engagement with the inner surface of the sleeve. The needles are thus rigidly held in the sleeve carried by the needle plate, and this sleeve is of a sufficient length to adequately support the shank of the needle preventing lateral displacement thereof in the reciprocation of the needle plate of the felting machine and effectively aids in preventing breakage of the needles. However, it will be understood that the novel form of felting needles hereinafter to be described may be mounted in the needle plate in any other suitable and known manner.

Referring now to Figure 4, in which a portion of the body portion of one form of needle of my present invention is shown on a greatly enlarged scale; it will be seen that at intervals along the edges 18 defined by intersections of adjacent side surfaces 19 of the needle, I provide spurs 20. These spurs are formed by means of suitable dies and comprise substantially triangular surfaces 21 extending inwardly of two adjacent side walls 19 forming a corner edge 18, which triangular surfaces extend downwardly and angularly so that the bases of the triangular surfaces 21 intersect to form a working edge 22 extending inwardly of the body of the needle from a corner 18 thereof. The die referred to also displaces metal below the spurs 20 to form a recess 23 and the material displaced in forming the spur and the recess 23 forms rounded protrusions 24 in the adjacent side walls. These protrusions in effect form integral flanges which materially increase the strength of the needle and the displaced metal is caused to flow into the portions of the body of the needle adjacent the recesses so that the cross-sectional area through the recess is substantially equal to the cross-sectional area of the stock from which the needle is made. It will be observed that a distinguishing characteristic of this form of spur is that the point of the spur does not extend beyond the corner edges 18, and the entire working portion of the spur comprises an edge 22 which effectively retains the fibers to be interlaced thereon eliminating any tendency of the fibers to creep toward the outer point of the spur.

In Figure 5 I have shown another form of felting needle which requires an additional step in its making over the needle of Figure 4. After the recess and spur have been formed in the body of the needle as described in conjunction with Figure 4, a second die of suitable configuration is caused to displace metal in the corner edge 18 immediately above the spur 20 so that the working edge 22 will have its outermost portion 25 of arcuate configuration with the outer point 26 of the spur directed downwardly and

disposed substantially within the plane of the corner edge 12 of the body 14 of the needle. In this form of the invention downward movement of the needle through a fibrous mass tends to cause the fibers to be forced up the working edge 22, 25 to be effectively retained by the needle for interlacing the fibers. In both forms of the needles herein disclosed it will be seen that the end wall of the recess is defined by a flat broad surface 27 extending at an angle of substantially 45° to the side walls of the needle. The bottom portion of the recess is defined by a flat triangularly shaped surface 28 extending downwardly and angularly to a corner edge from the bottom of the surface 27.

It will thus be observed that by means of the present invention I have provided a felting needle having a spur which comprises a working edge which may be disposed either at substantially right angle to the corner edge, or the outer portion of the working edge may be of arcuate configuration with the outer point thereof disposed inwardly of the corner edge and extending downwardly of the needle.

In Figure 6 I have shown diagrammatically one form of apparatus for forming spurs of the character described in conjunction with Figures 4 and 5, and it will be seen that it comprises a reel of metal stock 39, preferably of square configuration, as hereinbefore referred to, which is adapted to be fed through a straightener 32, through a series of male and female die block assemblies 33, which are arranged successively at right angles to each other and operate to form a recess and spur in the corner edges of the metal stock adjacent which they are positioned. In the embodiment shown in Figure 6 the stock is of square configuration and consequently four pairs of die blocks are provided, one pair for each corner edge. A wire feeding mechanism, illustrated diagrammatically at 35, is operable for drawing a length of wire substantially equal to the length of stock required to produce a single felting needle, and a blade 38 is provided for cutting the continuous strip of stock into needle lengths. The length of stock between the straightener and the feeder 35 is of a length to provide four needles, and since the pairs of die blocks 33 are arranged progressively at angles of 90° with respect to each other it will be seen that each pair of die blocks 33, when actuated, form a recess and spur of the character first described each in one corner edge so that in the stock disposed between the die blocks nearest the feeder is having a fourth recess and spur produced in it, and the next adjacent portion of stock is having a third recess and spur formed while the portion of stock ahead of it is having a second recess and spur formed, and the portion of stock disposed adjacent the first pair of die blocks is having a first recess and spur formed. All of the pairs of die blocks 33 are caused to be actuated simultaneously so that the stock in the pair of die blocks nearest the feeder will complete the spurs to be formed in that portion of stock and when advanced by the feeder is cut from the remainder of the stock by the blade 38. This severed portion is then pointed and provided with a securing element as described in conjunction with Figure 2 forming a completed needle. It will be understood that greater or fewer numbers of spurs may be formed in any single particular length of needle stock by providing fewer or greater number of pairs of die blocks 33 to provide a needle having the de-

sired number of spurs. I have found, however, that a needle of square cross-section having one spur formed in each corner edge will be efficient in operation.

5 The apparatus is readily adaptable for forming the felting needle of Figure 5 by providing additional pairs of die blocks 33 also positioned progressively successively at right angles to each other in the direction of travel of the stock, one pair each being arranged after each set of die blocks 33. The die blocks 33 may, like the die blocks 33, be operated simultaneously for displacing metal in the corner edges defining the spurs to form the spur shown in Figure 5.

15 While I have shown what I consider to be the preferred forms of the felting needles of my invention, and the apparatus and method for forming these spurs in the body of the needle, it will be understood that various rearrangements and modifications may be made therein without departing from the spirit and scope of my invention.

I claim:

1. As an article of manufacture, a felting needle comprising a body having an unrecessed portion and a recessed portion defining a downwardly directed spur, said body having protrusions adjacent its recessed portion the cross-sectional area of said recessed portion and said protrusions being substantially equal to the cross-sectional area of said unrecessed portion of said body.

2. As an article of manufacture, a felting needle comprising a body of polygonal cross-section having an unrecessed portion and provided in at least one corner edge with a recessed portion defining a downwardly directed spur lying within said corner edge, said body having protrusions adjacent its recessed portion the cross-sectional area through said recessed portion and said protrusions being substantially equal to the cross-sectional area of said unrecessed portion of said body.

3. As a new article of manufacture, a felting needle comprising a body provided with a recess therein, and a spur having a single material engaging edge formed by downwardly and angularly directed intersecting lateral surfaces, said edge extending inwardly of the needle adjacent the upper end of said recess.

4. As a new article of manufacture, a felting needle having a body of substantially uniform polygonal cross-section provided in at least one corner edge with a recess, and a spur having a single material engaging edge in said corner edge formed by downwardly and angularly directed intersecting lateral surfaces, said material engaging edge extending substantially radially of the needle adjacent the upper end of said recess.

5. As a new article of manufacture, a felting needle having a body of substantially uniform polygonal cross-section provided in at least one corner edge with a recess, a spur in said corner edge formed by downwardly and angularly inclined substantially triangular surfaces the bases of which intersect to define a working edge extending inwardly of the needle adjacent the upper end of said recess, and the walls of the needle defining said corner edge adjacent said recess being reinforced to strengthen the needle thereof.

6. As a new article of manufacture, a felting needle having a body portion of substantially uniform polygonal cross-section provided in at

least one corner edge with a recess formed by displacing material thereat to define a downwardly directed spur having a working edge extending inwardly of the body of the needle within the corner edge thereof and above the recess, the displaced material forming protrusions in the side walls defining said corner edge adjacent the recess so that the cross-sectional area of the needle through said recess is substantially equal to the polygonal cross-sectional area of the body.

7. As a new article of manufacture, a felting needle having a body of substantially uniform polygonal cross-section provided in at least one corner edge with a downwardly directed spur, said spur being defined by a pair of substantially triangular surfaces one in each side wall of the needle forming said corner edge, each of said triangular surfaces having one edge lying in the surface of its respective side wall and extending downwardly and outwardly toward said corner edge, and a second edge diverging downwardly away from said first edge, the bases of said triangular surfaces intersecting to define a working edge extending inwardly of the body of the needle from said corner edge.

8. As a new article of manufacture, a felting needle having a body of substantially uniform polygonal cross-section provided in at least one corner edge with a recess formed by displacing material and forming reinforcing integral protrusions in the adjacent side walls, a spur in said corner edge defined by a pair of substantially triangular surfaces each having one edge lying in the side walls defining said corner edge and extending downwardly and outwardly toward the same, and a second edge diverging away from said first edge, the bases of said triangular surfaces intersecting to define a working edge extending inwardly of the body of the needle from said corner edge.

9. As a new article of manufacture, a felting needle having a body of substantially uniform polygonal cross-section provided in at least one corner edge with a recess formed by displacing material and forming reinforcing integral protrusions in the adjacent side walls so that the transverse cross-sectional area through said recess is substantially equal to the polygonal cross-sectional area of the body, a spur in said corner edge defined by a pair of substantially triangular surfaces each having one edge lying in the side walls defining said corner edge and extending downwardly and outwardly toward the same, and a second edge diverging away from said first edge, the bases of said triangular surfaces intersecting to define a working edge extending inwardly of the body of the needle from said corner edge.

10. As a new article of manufacture, a felting needle having a body of substantially uniform polygonal cross-section provided in at least one corner edge with a recess formed by displacing material and forming reinforcing integral protrusions in the adjacent side walls, a spur in said corner edge defined by a pair of substantially triangular surfaces each having one edge lying in the side walls defining said corner edge and extending downwardly and outwardly toward the

same, and a second edge diverging away from said first edge, the bases of said triangular surfaces intersecting to define a working edge extending inwardly of the body of the needle from said corner edge, said working edge being arcuate with its outer point directed downwardly and lying within said corner edge.

11. As a new article of manufacture, a felting needle having a body of substantially uniform polygonal cross-section provided in at least one corner edge with a recess formed by displacing material and forming reinforcing integral protrusions in the adjacent side walls, a spur in said corner edge defined by a pair of substantially triangular surfaces each having one edge lying in the side walls defining said corner edge and extending downwardly and outwardly toward the same, and a second edge diverging away from said first edge, the bases of said triangular surfaces intersecting to define a substantially straight line working edge extending inwardly of the body of the needle substantially at right angles to said corner edge.

12. In combination, a needle plate, a sleeve of circular cross-section extending through said needle plate and supported at one end therein, and a felting needle of substantially uniform polygonal cross-section throughout its length extending through said sleeve and having the corner edges of its shank portion engaging the inner wall of said sleeve to restrain said needle against lateral movement.

13. In combination, a needle plate, a sleeve extending through said needle plate and supported at one end therein, and a felting needle of substantially uniform cross-section throughout its length extending through said sleeve, said sleeve and said felting needle being formed so that the shank portion of the latter is restrained by the sleeve against lateral movement.

14. As a new article of manufacture, a felting needle comprising a body portion and a spur having a single material engaging edge at its lower end formed between lateral surfaces of the spur.

15. As a new article of manufacture, a felting needle comprising a body portion and a spur having a single straight line material engaging edge at its lower end formed between lateral surfaces of the spur.

16. As a new article of manufacture, a felting needle comprising a body portion and a spur having a single arcuate material engaging edge at its lower end formed between lateral surfaces of the spur.

17. As a new article of manufacture, a felting needle comprising a body having a spur formed by downwardly converging intersecting surfaces defining at their vertex an edge adapted for line contact with material to be operated upon by said needle.

18. In combination, a needle plate, a sleeve of circular cross-section extending through said needle plate and supported at one end therein, and a felting needle extending through said sleeve and being formed so that its shank portion engages the inner wall of the sleeve to restrain the needle against lateral movement.

EDSON P. FOSTER.
